INVENTOR:
John Fritsche.

BY
Heidrich & Jaenisch.

ATTORNEYS.

UNITED STATES PATENT OFFICE.

JOHN FRITSCHE, OF MERION, PENNSYLVANIA.

VALVE MECHANISM FOR LIQUID-VENDING MACHINES.

Original application filed September 16, 1919, Serial No. 324,154. Divided and this application filed May 24, 1922. Serial No. 563,201.

To all whom it may concern:

Be it known that I, JOHN FRITSCHE, a citizen of the United States, residing at Merion, county of Montgomery, State of 5 Pennsylvania, have invented a new and useful Valve Mechanism for Liquid-Vending Machines, of which the following is a specification.

In a copending application Serial No. 10 324,154, filed September 16th, 1919, and of which the present application is a division, I have described and broadly claimed a novel liquid vending machine which is adapted to vend a plurality of liquids of different 15 natures upon the insertion of a predetermined check or coin, so that a measured quantity of each liquid will be discharged from the machine.

My present invention relates to the novel 20 valve mechanism for controlling the discharge of liquid from the machine and to the above ends my invention comprehends a novel construction and arrangement of valve mechanism which, as will be understood by 25 reference to my parent application aforesaid, is actuated by a manually actuated handle which becomes operative to actuate the valve mechanism on the insertion into 30 the machine of a coin or check of the proper denomination.

Other novel features of construction and advantage will hereinafter more fully appear in the detailed description and the appended claims.

For the purpose of illustrating my invention, I have shown in the accompanying drawings a typical embodiment thereof which is at present preferred by me, since this embodiment will be found in practice 40 to give satisfactory and reliable results. It is, however, to be understood that the various instrumentalities of which my invention consists can be variously arranged and organized and that my invention is not limited 45 to the precise arrangement and organization of these instrumentalities as herein shown and described.

Figure 1 represents, in sectional elevation, a portion of a liquid vending machine in 50 conjunction with which a valve embodying my invention is employed.

Figure 2 represents a section on line 2—2 of Figure 1.

Similar numerals of reference indicate 55 corresponding parts.

Referring to the drawings,

1 designates a double walled container which forms a chamber 2 to receive a temperature changing medium which surrounds the liquid in the inner container, the latter having an outlet 3 which communicates with a valve mechanism 4 embodying my invention. The valve mechanism is employed in conjunction with a pair of measuring cups 5 and 6, respectively, each of which is provided with its respective vent pipes 7 and 8, respectively. The valve mechanism 4 comprises a casing 9 having the inlet 10 and the outlet 11 and provided with the laterally extending branches 12 and 13 70 which communicate respectively with the measuring cup 5 and the measuring cup 6. The casing 9 is provided with a laterally extending cylindrical bore 15 at one end and 16 at its opposite end each of which opens 75 through the juxtaposed wall of the valve casing and are connected by means of a tapering valve seat 17 which latter contributes with the cylindrical bore 16 to form a shoulder 18. 80

19 designates a conical valve adapted to engage the valve seat 17 and provided with the ports 20 and 21. The valve 19 has projecting from it a stem 22 through which extends laterally a pin 23 which is adapted to 85 be received in the slots 24 of a shaft 25 which latter is also recessed, as at 26, to receive the stem 22. The shaft 25 is suitably journaled in the framework of the machine and has connected with it a driven gear 27. The shaft 25 is provided with an antifriction bearing 28 such as, for example, a ball bearing, which revolves within the cylindrical bore 15 of the valve casing. The valve 19 has extending from its forward end 90 the valve stem 29 on which is mounted a ball bearing 30 which is secured in position by means of nuts 31 one of which serves as a lock nut.

It will be seen that when the nuts 31 are 100 tightened the ball bearing 30 which abuts against the shoulder 18 will retain the valve

19 in proper relationship with respect to its seat 17. The bore 16 is closed by means of a plate 32 which is secured in position by means of fastening devices 33. The open 5 end of the bore 15 is closed by means of a plate 34 secured in position by means of the fastening devices 35 and having an aperture 36 through which the shaft 25 extends and in which if desired it may have a bearing. 10 Each of the branches 12 and 13 is connected in a similar manner with respect to its respective measuring cup, the branch 13, for example, being internally threaded at its outer end, as at 37, in order to receive 15 the threaded end of a coupling 38 which is seated against the lower end of a flanged nipple 39 which is in threaded engagement with the measuring cup 6 and a nut 40 is provided which secures the coupling member 20 38 and the nipple 39 together. The threaded boss 41 through which the passage 10 is formed passes through the outer wall of the double walled container and is provided with a nut 42 which secures it 25 in position, said boss 41 being in threaded engagement with the pipe 43 which communicates with the outlet 3.

My present type of valve is intended 30 to be employed in conjunction with a liquid vending machine which is manually controlled, the measuring cups being surrounded by the insulating material or the temperature changing medium in the space between the inner and outer walls of the 35 liquid container. The valve mechanism which controls the passage of liquid to be vended from a liquid container into the measuring cups and the discharge from a measuring cup is in close proximity to such 40 liquid container so that the liquid will be retained in a heated or cold condition at substantially the same temperature as the temperature of the liquid in the liquid container.

45 In devices of this character as heretofore employed where it is necessary to employ a source of heat to maintain the liquid to be dispensed in a heated condition difficulty has always arisen owing to the binding and sticking of the valves. It has been found 50 in practice that when a valve constructed in accordance with my present invention is employed this binding and sticking of the valve does not take place.

55 It will now be apparent that I have devised a new and useful valve mechanism for liquid vending machines which embodies the features of advantage enumerated as desirable in the statement of the invention 60 and the above description, and while I have, in the present instance, shown and described a preferred embodiment thereof which will give in practice satisfactory and reliable results, it is to be understood that this em-

bodiment is susceptible of modification in 65 various particulars without departing from the spirit or scope of the invention or sacrificing any of its advantages.

Having thus described my invention, what I claim as new and desire to secure 70 by Letters Patent, is:

1. In a liquid vending machine, a valve casing having a plurality of ports and provided with a bore having a tapered valve seat therebetween and through which said 75 ports open, said bore having a cylindrical portion forming with said seat a shoulder a conical valve to engage said seat, a ball bearing, and means to secure said ball bearing to said valve whereby said ball bearing 80 engages said shoulder and serves to secure said valve in proper relation with respect to said ports and also as an antifriction bearing.

2. In a liquid vending machine, a valve 85 casing having a plurality of ports, a longitudinal bore provided with a tapered valve seat into which said ports open and cylindrical portions at each end, one of which forms with said valve seat a shoulder, a 90 valve to engage said seat and having a plurality of ports to be brought into register with predetermined ports in the casing, and a ball bearing for said valve at each end thereof, one of said bearings engaging 95 said shoulder and serving to retain said valve in engagement with said seat.

3. A valve mechanism, comprising a valve casing having cylindrical bores of different diameters, a tapered valve seat forming with 100 one of said cylindrical bores a shoulder, an inlet and an outlet port communicating with said seat, and a plurality of passages communicating with said seat, a two-way valve engaging said seat and having a stem 105 at each end, a ball bearing carried by one stem and engaging said shoulder to retain said valve in position, and driving means to interlock with said other stem.

4. A valve mechanism, comprising a casting having a differential bore including a tapered valve seat, a cylindrical portion forming with said seat a shoulder and provided with a main inlet port, an outlet 110 port and a plurality of branches communicating with said seat, a two-way valve engaging said seat, a ball bearing for said valve engaging said shoulder to retain it in position, a pin carried by said valve, a driven shaft having means to engage said 115 pin, and a ball bearing for said driven shaft.

5. A valve mechanism, comprising a valve casing having a differential bore opening through opposite ends forming a shoulder and provided with a valve seat, a multiple way valve engaging said seat, a ball bearing carried by said valve and adapted to 120 125

engage said shoulder to secure it in position, said valve having a stem at one end, a driven shaft having means to interlock with said stem, a ball bearing within said bore for said driven shaft, and a closure for one end of said bore to retain said shaft in operative engagement with said valve, said casing having ports controlled by said valve.

JOHN FRITSCHE.
